Primary Examiner — Susan E Krakower*Assistant Examiner* — Ramzi Almatrahi(74) *Attorney, Agent, or Firm* — Salter & Michaelson**(57) CLAIM**

The ornamental design for a combined camera and housing, as shown and described.

DESCRIPTION

FIG. 1 is a front elevational view of a first embodiment of a combined camera and housing;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of a second embodiment of a combined camera and housing;

FIG. 8 is a rear elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The broken lines depict portions of a combined camera and housing in which the design is embodied and form no part of the claimed design.
